REFRIGERATOR CABINET

George William Walker, Bloomfield Hills, Mich.,
assignor to International Harvester Company, a corporation of New Jersey

Application December 22, 1949, Serial No. 6,780

Term of patent 7 years

(Cl. D67—3)

To all whom it may concern:

Be it known that I, George W. Walker, a citizen of the United States, residing at Bloomfield Hills, in the county of Oakland and State of Michigan, have invented a new, original, and ornamental Design for Refrigerator Cabinet, of which the following is a specification, reference being had to the accompanying drawings, forming part thereof, in which:

I claim:

The ornamental design for a refrigerator cabinet, as shown.

GEORGE WILLIAM WALKER.
